MOWER.

APPLICATION FILED NOV. 25, 1903.

UNITED STATES PATENT OFFICE.

GEORGE DOAN JOHNSON AND JACOB HENRY JOHNSON, OF HUNTSVILLE,
CANADA.

MOWER.

No. 806,259.

Specification of Letters Patent.

Patented Dec. 5, 1905.

Application filed November 25, 1903. Serial No. 182,657.

To all whom it may concern:

Be it known that we, GEORGE DOAN JOHNSON, merchant, and JACOB HENRY JOHNSON, builder, of the town of Huntsville, in the district of Muskoka, in the Province of Ontario, Canada, have invented certain new and useful Improvements in Mowers, of which the following is a specification.

Our invention relates to improvements in mowers; and the object of the invention is, first, to devise a simple, cheap, and durable drive for the knife-bar which will not be liable to come in contact with obstructions on the surface of the field; secondly, to form such a connection between the driving means and knife-bar which will without throwing out the driving means not allow of motion to the knife-bar in the raised position and the consequent racking of the machine incident to such motion, and, thirdly, to provide means for raising the finger-bar which will relieve the driver of the machine to a great extent of the weight of the bar, in raising will be more convenient to operate, and will allow of the bar to fall so gradually as not to rack the same, and which will also support the major portion of the weight of the finger-bar, so that it will rest lightly on the ground and thereby the draft be decreased. To carry out these objects, we have constructed and arranged our mower in detail as hereinafter more particularly explained.

Figure 1 is a perspective view of the mower, showing the parts involved in our invention, portions being broken away for the sake of clearness. Fig. 2 is a front elevation of the finger-bar, showing the connection of the driving means to the knife-bar. Fig. 3 is a view showing a portion of the lifting-lever and quadrant from the side opposite to that shown in Fig. 1. Fig. 4 is a perspective view of the cam. Fig. 5 is a section of the cam, showing the form of cam and roller.

In the drawings like characters of reference indicate corresponding parts in each figure.

A is the axle, and B the wheels.

C is the swinging frame, through which the axle extends and which is substantially triangular in form, extending at one side substantially parallelly with the plane of the wheel to the rear of the finger-bar D.

E is the tongue, which is secured on a suit-

able bracket e, pivotally connected to the frame C.

F is the shoe, to which the inner end of the finger-bar is secured.

c is a boss formed at the front apex of the frame C, and c' is a pivot-pin which extends through the boss c and the bracket f at the rear of the shoe.

G is the knife-bar, having the usual heel g at the inner end.

H is a lever, which is pivoted on the bolt h, extending upwardly from the boss c' on the frame C.

C' is the rearward extension-frame of the frame C, which extends upwardly and is provided with the bosses c', connected by the bar c' at the top and the rib c' at the bottom, such bosses with the rib and bar forming a guide and support for the lever H in its oscillating movement, as will hereinafter appear. The extension C' has bearing-bosses C', in which is journaled one end of the cross-shaft I.

Between the bearing-bosses C' on the shaft I we provide a cam-wheel J.

C' is a rearward extension of the frame C at the opposite end, such rearward extension carrying the bearing-bosses C', through which the shaft I extends.

K is a pinion on the end of the shaft I, which meshes with the gear-wheel L, secured on the axle A.

Suitable means k, not necessary here to describe, are provided for throwing the pinion in and out of gear.

The cam-wheel J is provided with a serpentine way j, the inwardly-extending apexes j' of which are perpendicular to the bottom or inner periphery of the cam. The opposite corresponding recess is rounded and inclines inwardly at the bottom, so as to permit of easy movement of the roller h' at the end of the lever; which, it will be noticed, is a tapered roller with the shortest diameter at the inside. The roller h' is journaled on a pin h', extending through the end of the lever.

It will be noticed that the axis of the roller is at right angles to the lever and on a line with the radial line passing through the center of the shaft I.

By the peculiar construction of the roller h' and of the cam the roller as the cam re-

volves will have a continuous sinuous movement without jar or break of the continuity of such movement, as such roller will continue to roll as it passes from the apex j' of one side j into the recess j'' of the opposite side, so as to pass along that side. In other words, there will be no jumping of the roller from one side to the other, but a continuous rotation of the roller as it follows the sinu-
10 osity of the cam.

The lower end of the lever H is bent and has a ball secured thereto which fits in a socket formed by a forked end of a link M. Thus a ball- and -socket connection m is formed at this point. The other end of this link is bent and is connected to a pin g' , which extends through the heel g of the knife-bar G.

When the knife-bar is at the beginning of its stroke, the lever H, knife-bar, and link M are arranged so that the connection between the lever and link M is located to the inside of the fulcrum of the finger-bar. By this arrangement when the stroke is made the connection m travels to a point to the opposite side of the fulcrum equidistant from it. It will be seen that when the knife is in the raised position there will be much less motion to it than if the connection was located 20 in any other position.

By reducing the motion when the knife-bar is in the raised or inoperative position it reduces the wear on the knife-bar, yet at the same time when the knife-bar is in the operative position the arrangement allows of a maximum length of stroke to it.

It will now be understood that as the shaft I is caused to rotate the cam J imparts a reciprocating movement to the link M, and consequently to the knife-bar.

In order to raise the knife-bar, we provide the following device: N is a lever, which is pivoted on a pin n , extending through a bracket O, attached to or forming part of the frame C. The bracket O is provided with a quadrant o and the lever N with a suitable plunger N' , designed to coat with such bracket and operate in the usual manner. P is a supplemental lever, which is pivoted on 45 an extension O' of the bracket O and provided at the upper end with a roller p , which is held so as to run in a guideway n^2 , secured to or forming part of the lever N, by means of a spiral spring Q, connected to the rear 50 lower bent end of the lever P at one end and to an eye-bolt r , extending through the bracket R, attached to the tongue or pole.

It will be noticed that the point of connection of the spiral spring Q at the lower end of the lever P is beneath a line extending between the end of the bracket R and the upper portion of the frame C, supported on the axle A, and it will consequently be understood that the tendency of the spring Q at all 60 times is to exert an upward pull on the front

portion of the frame C, and consequently on the finger-bar, thereby serving to cause such finger-bar to rest lightly on the ground, depending on the tension of the spring, thus materially assisting in reducing the draft.

The lower end of the lever N is connected by a link or rod 2 to one or the other of the holes 3 in the rear of the shoe F. It will thus be understood that not only does the spring Q serve the purpose hereinbefore referred to, but also when the lever N is manipulated and drawn in the direction indicated by arrow such spring Q pulling upon the lower end of the lever P will press the roller p against the lever N, thereby materially assisting the driver of the machine in raising the finger-bar. In fact, so much so does the spring serve this purpose that with but a slight quick exertion on the top of the lever N the finger-bar will be raised into the position shown in dotted lines in Figs. 1 and 2, and in which position it would be held by the plunger N' coming in contact with the rear of the quadrant O.

Upon the plunger N' and the lever N being released the spring Q, counterbalancing the weight of the finger-bar, will serve to allow such finger-bar to pass gently back to the working position, which is an important desideratum, as it avoids the racking of such bar.

It will be noticed on reference to Fig. 2 that when the finger-bar is raised into the position shown in dotted lines such link M is raised to the vertical position, and as the movement of the front lower end of the lever H is a horizontal movement to the inside of the pivot-pin c' , extending through the shoe of the finger-bar, such movement of the lever will not communicate any appreciable motion to the knife-bar, thereby serving to prevent any racking of the machine, and consequently it will be unnecessary to throw out the gear. In fact, we only throw out the gear-drive when we are not using the machine, but driving long distances.

From this description it will be seen that we have produced a mower with a less number of parts than those at present in use and less liable to wear and tear, lighter, more durable, and in which all the working parts are perfectly protected from obstructions in the field, and in which the draft is reduced to a minimum.

What we claim as our invention is—

1. In a mower, the combination of the finger-bar, the knife-bar arranged to reciprocate on the finger-bar, a frame on which the finger-bar is pivoted, a lever pivoted intermediate its ends to the frame at right angles to the knife-bar, means at one end of said lever for oscillating the same horizontally, a link M having a ball-and-socket connection with the lower end of said lever, said link M having a bent end which is connected with the knife-

130

bar near the axis of the pivot of the finger-bar so as to give the knife-bar reciprocating movement when the lever is reciprocated and means for raising the finger-bar with the 5 knife-bar into vertical position whereby the point of connection of the link M with the knife-bar will be carried above the plane of movement of the lever so that the lower end of the link M will oscillate while the upper end 10 is substantially stationary, substantially as described.

2. In a mower, the combination with the wheels, swinging frame and finger-bar pivotally connected to the same, and a lifting-lever pivoted on the swinging frame, and the 15 link connecting the bottom end of the lever to the finger-bar, of means coacting with the lever for reducing the weight of the finger-bar as it is being raised as and for the purpose specified.

3. In a mower, the combination with the wheels, swinging frame and finger-bar pivotally connected to the same, and a lifting-lever pivoted on the swinging frame, and the 20 link connecting the bottom end of the lever to the finger-bar, of a supplemental lever pivoted on the swinging frame and having one end designed to come in contact with the lever, and a spiral spring connecting the opposite end of the lever to the pole or tongue 25 as and for the purpose specified.

to the finger-bar, of a supplemental lever pivoted on the swinging frame and having one end designed to come in contact with the lever, and a spiral spring connecting the opposite end of the lever to the pole or tongue 30 as and for the purpose specified.

4. In a mower, the combination with the wheels, swinging frame and finger-bar pivotally connected to the same, and a lifting-lever pivoted on the swinging frame, and the 35 link connecting the bottom end of the lever to the finger-bar, a guide on said lever of a supplemental lever pivoted on the swinging frame a roller at one end thereof designed to come in contact with said guide on the first- 40 mentioned lever, and a spiral spring connecting the opposite end of the supplemental lever to the pole or tongue as and for the purpose specified.

GEORGE DOAN JOHNSON.
JACOB HENRY JOHNSON.
